UNITED STATES PATENT OFFICE.

FOREST OKEY KELFER, OF HEALDTON, OKLAHOMA.

AWNING.

Application filed November 11, 1925. Serial No. 68,350.

My invention is an awning for shading a window or other opening in a dwelling house, closed automobile, railway train, or like structure, and it consists in the combinations, constructions and arrangements herein described and claimed.

An object of the invention is the provision of an awning of the character described which affords facilities for shading a window or opening with which the awning is associated without preventing circulation of air between the awning structure and the window or opening with which the awning is associated.

A further object of the invention is the provision of an awning of the character described which can be adjusted so that a shade member of a given width which is comprised in the awning will be effective to shade a window or opening having a width equal to that of the shade member during the entire period of sunlight each day.

A further object of the invention is the provision of an awning of the character described which comprises a flexible shade member and means for supporting the shade member in association with a window or other opening so that the shade member can be adjusted both vertically and horizontally. A still further object of the invention is the provision of an awning of the character described having a horizontally swingable frame for supporting a flexible shade member, the frame being adapted for connection through the medium of suitable motion transmitting means with the frames of other awnings of the same kind and located at the same level, whereby a plurality of the awning frames can be connected in series so that bodily swinging movement of one of the awning frames will cause like swinging movement of the remaining awning frames of the series.

Other objects and advantages of the invention will be apparent from the following description, considered in conjunction with the accompanying drawings, in which

Figure 1 is a perspective view showing two windows located at the same level and equipped with awnings embodying the invention.

Figure 2 is a relatively enlarged horizontal section through the frame of one of the awnings which are exhibited in Figure 1 and through the supporting structure for said awning, one position of the awning being in-

dicated by full lines and a second adjustment of the awning frame being indicated by dotted lines.

The frame of the awning embodying the invention comprises a pair of side members, each of which is of rod-like form and comprises parallel upper and lower attaching end portions 1 and 2 respectively, and a main or body portion 3. The body 3 of each frame member of the awning is perpendicular to the planes of the attaching end portions 1 and 2 for the greater part of its length from its juncture with the lower attaching end portion 2 and then is inclined 70 from the perpendicular for the remainder of the distance to its juncture with the attaching end portion 1, the latter being of less length than the attaching end portion 2 but preferably terminating at its extremity 75 flush with the extremity of the attaching end portion 2 of the same frame member.

The side members of the frame of the awning are connected and are maintained in spaced parallel relation by means of an upper cross bar 4 and spaced lower cross bars 5 and 6, respectively. The upper cross bar 4 extends between the upper attaching end portions 1 while the lower cross bars 5 and 6 extend between the lower attaching end portions 2 and each of these cross bars is attached at its opposite ends by vertical pivot elements 7 to clips 8 which are secured on the end portions of the side members of the awning frame. The extreme end portions 90 of the parts 1 of the side members of the awning frame are flat and are provided with vertical apertures for the reception of the upturned pivot elements 9 which are shown as being upturned end portions of fastening rods 10. The fastening rods 10 are fast in the opposite end portions of the upper cross member 11 of the frame structure of a window 12. The extreme end portions of the parts 2 of the awning frame likewise are 100 flattened and are provided with vertical apertures for the reception of the upturned end portions 13 of fastening rods 14 which are fast in the frame structure of the window at opposite sides of the latter and at the lower end of the window, each upturned pivot element 13 being in vertical alignment with the corresponding pivot element 9. With this arrangement, the side members of the awning frame can swing in unison horizontally.

An operating lever 15 is pivotally attached

at its outer end by a vertical pivot element 16 to the cross bar 5 intermediate the length of the latter and extends inwardly across the cross bar 6 onto the horizontal member 5 of the frame structure of the window. A vertical pivot element 17 connects the operating lever 15 to the cross bar 6 at a point intermediate the length of the operating lever and the inner end portion of the lever 15 slides on an arcuately curved guide bar 18 which is attached at its ends in any suitable known manner to the cross bar 6. The extreme inner end portion of the lever 15 is turned upwardly as indicated at 19 to produce a handle. A clamping jaw 20 is adjustably secured to the lever 15 by a thumb screw 21 and bears against the underside of the tire 18. The thumb screw 21 can be tightened to cause the clamping jaw 20 to engage with the guide bar 18 so that the operating lever 15 will be releasably held against swinging movement from adjusted position about the axis of the pivot element 17.

25 A shade member which is comprised in the awning may be a sheet of canvas or other flexible material such as indicated at 22. This shade member is provided at its upper and lower ends with cross rods 23 and 24 respectively which are secured to the upper and lower end portions of the shade member 22 in any suitable known manner, as by being received in hems in the upper and lower end portions of the shade member.

30 The ends of the cross rods 23 and 24 carry eye members 25 which slidably embrace the side members of the awning frame and the shade member 22 may be provided with other eye members 26 which are spaced along the side edges of the shade member and also slidably embrace the side members of the awning frame. A third cross rod 27 may be supported in a hem in the shade member 22 intermediate the upper and lower ends of the latter and this third or middle cross rod 28 has eye members 28' at the opposite ends thereof in sliding and embracing relation to the side members of the awning frame. A cable 29 has branches 30 attached to the lower cross rod 24 of the shade member. A second cable 31 is attached at one end to the middle cross rod 27 of the shade member intermediate the ends of said middle cross rod and a third cable 32 is attached at one end to the middle portion of the upper cross rod 23 of the shade member. These cables 29, 31 and 32 extend through the guide ring 33 which depends from the middle portion of the upper cross bar 4 of the awning frame. The free ends of the cables 29, 31 and 32 can be grasped and manipulated as desired to adjust the shade member 22 between the side members of the awning frame and when a desirable adjustment has been effected, the free end portions

of the cables can be secured to a suitable fastening device, such as indicated at 34 on a member of the frame structure of the window 12. It will be obvious that the shade member can be raised to the upper 70 part of the awning frame, lowered to the lower part of the awning frame or extended as shown in the right hand portion of Figure 1 to cover practically the entire space between the bodies or main portions of the 75 side members of the awning frame.

Stops 35 on the side members of the awning frame adjacent to the lower ends of the body of said side members limit the downward movement of the ring or eye members 80 25 and thus limit the downward movement of the lower end portion of the shade member between the side members of the awning frame. The upper cross bar 4 between the side members of the awning frame of course 85 will constitute a stop for limiting the upward movement of the upper end of the shade member between the side members of the awning frame.

A canopy 36 which may be made of a 90 light gauge metal or other suitable material and which preferably is arcuately curved in cross sectional contour with the convexly curved face thereof uppermost may be provided to extend between the side members 95 of the awning frame at the juncture of the upper attaching end portions 1 and the bodies of the side members of the awning frame, this canopy being attached at its inner edge in any suitable known manner 100 to the cross bar 4.

From the foregoing description of the various parts of the device, the operation thereof may be readily understood. The side members of the awning frame and of course the shade member which is carried between the side members of the awning frame can be swung toward the right or toward the left from position directly in front of the window 12. Therefore, shade can 110 be provided for the window 12 at all hours during the day by adjustment of the frame of the awning horizontally when the shade member has a width that is not greater than the width of the window. When a plurality of windows which are located at the same level are provided with awnings embodying the invention, the side members of adjacent awnings can be connected by means of a connecting rod 37 having the opposite 120 end portions thereof attached by vertical pivot elements 38 to the outwardly turned arms 39 of brackets 40 which are secured to the lower end attaching portions 2 of the side members of the awning frame and a 125 plurality of the awnings thus can be swung horizontally in union as a result of actuation of the operating lever 15 of one of the awnings.

It will be observed that the shade member 130

of the awning is supported sufficiently far from the window and is spaced at its upper and lower ends from the window so that circulation of air between the window and the shade member is permitted when the shade member is in position to provide shade for the window.

While I have shown the improved awning applied to a window of a building, it will be manifest that the awnings may be employed to shade the windows or other openings in structures, such as the bodies of closed automobiles or railway passenger trains.

The invention obviously is susceptible of embodiment in forms other than that which is illustrated in the accompanying drawing, and I therefore consider as my own all such modifications and adaptations thereof as fairly fall within the scope of the appended claims.

I claim:—

1. An awning comprising a frame, means for supporting said awning frame on the frame structure of a window or other opening so that said awning frame may swing horizontally, and a flexible shade member carried by said awning frame in spaced relation to said window, said shade member being adjustable vertically along said awning frame while said awning frame remains stationary, whereby said shade member may be lowered bodily on the awning frame from the top of the latter or raised bodily on the awning frame from the bottom of the latter.

2. In an awning, a frame comprising a pair of side members of rod-like form, said side members having relatively long body portions joined at their opposite ends to attaching end portions, the attaching end portions of each side member being parallel, means engageable with the attaching end portions of said side members for supporting the side members with the body portions thereof substantially vertical adjacent to the frame of a window and so that said side members can swing horizontally, and a flexible shade member having eye members at the side edges thereof slidably embracing the body portions of said side members of the awning frame, whereby said shade member may be moved bodily along said side members of the awning frame while said awning frame remains stationary.

3. In an awning, a frame comprising a pair of side members of rod-like form, said side members having relatively long body portions joined at their opposite ends to attaching end portions, the attaching end portions of each side member being parallel, means engageable with the attaching end portions of said side members for supporting the side members with the body portions thereof substantially vertical adjacent to the frame of a window and so that said

side members can swing horizontally, and a flexible shade member having eye members at the side edges thereof slidably embracing the body portions of said side members of the awning frame, cross members between the attaching end portions of said side members of the awning frame, said cross members being attached at their opposite ends to the adjacent attaching end portions of the side members of the awning frame to swing about vertical axes, and an operating lever fulcrumed intermediate its ends on a cross member between the lower end portions of side members of the awning frame and pivotally attached at one end to an adjacent cross member between said side members of the awning frame, said operating lever thus being adapted to be actuated to effect swinging movement of the awning frame horizontally.

4. In an awning, a frame comprising a pair of side members, each of rod-like form comprising an upright body portion having horizontal parallel attaching end portions, said attaching end portions having vertical apertures for the reception of vertical pivot elements for supporting said side members at opposite sides of a window frame and for swinging movement horizontally, a cross bar between the upper attaching end portions of said side members, said cross bar being pivotally connected at its opposite ends to said upper attaching end portions, a pair of spaced cross bars between the lower attaching portions of said side members of the window frame, said lower cross bars being pivotally connected at their opposite ends to the lower end attaching portions of the side members of the awning frame, an operating lever fulcrumed intermediate its length on the inner lower cross bar and pivotally connected at its outer end to the other lower cross bar, an arcuately curved guide bar attached at its ends to the inner lower cross bar, cooperating means carried by said operating lever and said arcuately curved bar for locking said operating lever to said arcuately curved guide bar, and a flexible shade member adjustably supported on the bodies of said side members of the awning frame.

5. In an awning, a frame comprising a pair of side members, each of rod-like form comprising an upright body portion having horizontal parallel attaching end portions, said attaching end portions having vertical apertures for the reception of vertical pivot elements for supporting said side members at opposite sides of a window frame and for swinging movement horizontally, a cross bar between the upper attaching end portions of said side members, said cross bar being pivotally connected at its opposite ends to said upper attaching end portion, a pair of spaced cross bars between

the lower attaching portions of said side members of the window frame, said lower cross bars being pivotally connected at their opposite ends to the lower end attaching portion of the side members of the awning frame, an operating lever fulcrumed intermediate its length on the inner lower cross bar and pivotally connected at its outer end to the other lower cross bar, an arcuately curved guide bar attached at its ends to the inner lower cross bar, cooperating means carried by said operating lever and said arcuately curved bar for locking said operating lever to said arcuately curved guide bar, a flexible shade member adjustably supported on the bodies of said side members of the awning frame, and cables connected to the upper and lower ends of said shade member and to the middle portion thereof for adjusting the shade member vertically along said side members of the awning frame.

6. In an awning, a frame comprising a pair of rod-like side members having standing body portions and horizontal upper and lower end portions adapted to be swingingly attached to vertical pivot elements, the body portions of said side members being inclined slightly adjacent to their upper ends toward the plane of the support

for said side members of the awning frame, 30 and a flexible shade member slidably supported at its side edges on the bodies of said side members of the awning frame and being bodily adjustable along the side members of the awning frame either from the top 35 or the bottom of the awning frame.

7. An awning having a frame comprising a pair of side members, each of rod-like form and each having parallel upper and lower end portions and a substantially vertical body portion, means supporting the end portions of said side members of the frame so that said side members can swing horizontally at the same level about parallel axes, cross bars pivotally attached at their ends to the end portions of the respective side members of the awning frame, a shade member adjustably supported between the body portions of the side members of the awning frame, and an attaching member 40 extending outward from the end portion of a side member of the awning frame, said attaching member being adapted for pivotal connection with a motion transmitting element for connecting said attaching member with a similar attaching member on an adjacent awning frame. 45
